CIRCUIT BREAKER

Francis L. Gelzheiser, Pittsburgh, Pa., assignor to
Westinghouse Electric Corporation, East Pittsburgh, Pa., a corporation of Pennsylvania

Application April 12, 1952, Serial No. 281,981

11 Claims. (Cl. 200—116)

1

This invention relates to circuit breakers and more particularly to circuit breakers for controlling lighting and moderate power circuits.

An object of the invention is to provide a circuit breaker which is of simple and rugged construction, safe and reliable in operation, and which is inexpensive to manufacture.

A second object of my invention is to provide a trip-free circuit breaker operated by a toggle which is normally supported at its knee by a member movable in response to an overload to permit collapse of the toggle and opening of the contacts independently of the handle.

Another object of the invention is to provide a circuit breaker in which the movable switch member forms a part of the operating toggle supported in an underset operative position by a pivoted trip member which is actuated by stored energy means to effect automatic opening of the breaker.

Another object of the invention is to provide a circuit breaker embodying a trip member which is actuated by stored energy means to cause opening movement of a movable switch member, the trip member having means thereon for engaging and starting the switch member in opening direction.

Another object of the invention is to provide a circuit breaker embodying a stored energy trip device which is releasably restrained by a thermally responsive trip element and operable upon release to cause automatic opening of the breaker, energy being stored in said device by resetting movement of the breaker mechanism.

The novel features that are considered characteristic of the invention are set forth in the appended claims. The invention itself, however, both as to structure and operation, together with additional objects and advantages thereof, will be best understood from the following detailed description thereof when read in conjunction with the accompanying drawings.

In said drawings:

Fig. 1 is a side elevational view with the cover removed of a circuit breaker embodying the principles of the invention, the breaker being shown in the closed-circuit position;

Fig. 2 is a view similar to Fig. 1 but showing the parts in the manually-opened position;

Fig. 3 is a view similar to Fig. 1 but showing the parts in the tripped-open position;

Fig. 4 is a horizontal sectional view taken along line IV—IV of Fig. 1.

Referring to Fig. 1 of the drawings, the circuit breaker comprises generally a housing 11

2

and a cover plate 13 (Fig. 4) both of molded insulating material, stationary contact means 15 and cooperating movable contact means 17, an operating mechanism indicated generally at 19 and a trip device indicated generally at 21.

The stationary contact 15 is rigidly mounted on the inner end of an angular conducting strip 23 which extends out through an opening in the adjacent end wall of the housing 11 and has a terminal connecting means 25 at the outer end thereof. The movable contact 17 is rigidly mounted on one end of a switch actuating member 27 having its other end pivotally connected by means of a knee pivot pin 29 to a pair of spaced toggle links 31 pivotally mounted on a pivot pin 33 supported in companion openings in the side wall of the housing 11 and in the cover plate 13. The toggle links 31 form an underset toggle with the switch arm 27. The switch actuating member 27, at a point adjacent the pivot pin 29, is connected by means of a flexible conductor 35 to a bimetal trip element 37 which is mounted by means of a screw 39 on one end wall of the housing 11. The other or free end of the bimetal element is connected by means of a flexible conductor 41 to the inner end of a conducting strip 43 which extends through an opening in the end wall of the housing 11 and has a terminal connector 45 on its outer end.

A pair of overcenter springs 47 disposed one on each side of the switch member 27 has one end hooked over a pin 49 in the switch member and the other end connected by means of an extension 51 to an arcuate operating handle 53. The handle 53 is disposed for sliding movement in an arcuate groove 55 in the housing 11 and in a companion groove (not shown) in the cover plate 13. The handle 53 is of molded insulating material and has a finger piece 57 molded integral therewith which extends out through an opening 59 in the housing 11.

In the closed position of the parts, a projection 61 on the switch member 27 adjacent the knee pivot pin 29 is held in engagement with the periphery of a trip member 63 by the overcenter springs 47 which are overcenter to the right of the knee pivot pin 29. In this position, the springs 47 bias the switch member 27 closed. The trip member 63 is made of molded insulating material and is pivotally mounted by means of trunnions 65 molded integral therewith which engage in companion openings in the side wall of the housing 11 and in the cover plate 13. The trip member is biased to the position shown in

Fig. 1 by means of a spring 67 disposed in a notch in the cover plate 13 (Fig. 4) and engaging a flat portion of the adjacent trunnion 65.

Molded integral with the trip member 63 is a projection 69, the free end of which, in the normal or closed position of the trip member, lies adjacent and in the path of movement of one end of a trip actuator 71 pivotally mounted on a pin 73 supported in openings in the side wall of the housing 11 and in the cover plate 13. The trip actuator 71 is biased in a counterclockwise direction about the pin 73 by means of a spring 75 connected under tension between the trip actuator 71 and a pin 77 supported in the housing 11 and cover 13. The trip actuator 71 is normally releasably restrained by engagement of a latching end 79 thereof with a latch member comprising an adjusting screw 81 threadedly mounted in the bimetal element 37.

All of the parts, except the bimetal element, are removably mounted through the open side of the housing 11 and are supported and positioned in the housing by means of surfaces and recesses, molded in the housing 11 and in the cover 13 without being positively fastened to the housing or cover.

The circuit breaker is manually opened by manipulation of the handle 53. Movement of the handle toward the left from the position in which it appears in Fig. 1 to its Fig. 2 position carries the line of action of the overcenter springs 47 over to the left of the pivot pin 29 where the overcenter springs bias the switch member 27 in opening direction and move the switch member clockwise about the pivot 29 to open the contacts with a snap action. The opening movement of the switch member is limited by means of a stop 83 molded integral with the base of the housing 11. The parts are shown in the manually opened position in Fig. 2.

The contacts are closed by reverse movement of the handle 53 from the position shown in Fig. 2 back to the closed position. This movement of the handle carries the line of action of the overcenter springs 47 across to the right of the pivot pin 29 whereupon the overcenter springs move the switch arm 27 to the closed position to close the contacts with a snap action.

The circuit breaker is tripped open automatically by thermal bending of the bimetal element 37 when heated in response to overload currents. Upon the occurrence of an overload current, the bimetal element 37 becomes heated and, when heated a predetermined amount, bends toward the left (Fig. 1) causing the latch 81 to release the trip actuator 71 whereupon the spring 75 snaps the trip actuator counterclockwise about its pivot 73 against a limit stop 85 projecting inwardly from the cover plate 13. This movement of the trip actuator 71 acts on the projection 69 of the trip member 63 to snap this member clockwise to the position shown in Fig. 3, during which movement a recess 87 in the trip member 63 is moved to a position beneath the projection 61 on the switch member 27. At this time, a component of the force of the overcenter springs 47 causes the projection 61 to move into the recess 87 which action carries the knee pivot pin 29 across to the right of the line of action of the overcenter springs. This causes collapse of the toggle 27-31 and movement of the switch member 27 to the open position to open the contacts with a snap action. At the same time, the projection 61 moves into the recess 87 the springs 47 move the switch member 27 upwardly causing

further collapse of the toggle 27-31 and causing further clockwise rotation of the trip member 63 until its movement is arrested by engagement of a projection 89 thereon with a projection 91 on the handle 53.

Should the contacts stick on an automatic operation, the clockwise rotation of the trip member 63 under the influence of the spring 75 will cause a projection 89 on the trip member to strike a portion 95 of the switch member 27 and start the switch member in opening direction. The parts are shown in the automatically tripped open position in Fig. 3.

Before the contacts can be closed following an automatic opening operation, it is necessary to reset the trip member 63 to its operative position (Fig. 1) and to reset and relatch the trip actuator 71. This is accomplished by movement of the handle 53 to the open position as shown in Fig. 2. During this movement the projection 91 on the handle engages the projection 89 on this trip member 63 and rotates this member counterclockwise to its Fig. 2 position, and this movement of the trip member 63 causes the projection 69 thereon to engage the trip actuator 71 and move the latter clockwise to its latched position. During the latter portion of this movement, the beveled latch end 79 of the trip actuator wipes by the latch member 81 slightly bending the bimetal element 37. Thereafter the bimetal element resumes its normal position, reengaging the latch 81 with the latch end 79 of the trip actuator 71. Also, during the counterclockwise resetting movement of the trip member 63, a cam surface 97 at the end of the recess 87 in the trip member engages the projection 61 on the switch member 27 and moves the knee of the toggle 27-31 to the position shown in Fig. 2, where the projection 61 rests on the annular periphery of the trip member 63. This moves the knee pivot pin 29 to the left to its Fig. 2 position. The contacts are then closed in the previously described manner by movement of the handle 53 from the position shown in Fig. 2 back to the Fig. 1 position.

The invention provides a circuit breaker in which the movable switch member forms a part of the operating toggle and is supported in operative position by a pivoted trip member. The trip member is actuated to effect automatic opening of the contacts by a stored energy means which is released by a thermally responsive trip device. The trip member is provided with means actuated by the stored energy means for engaging and starting the switch member in opening direction should the contacts stick.

Having described the invention in accordance with the provisions of the patent statutes, it is to be understood that various changes and modifications may be made in the structural details and arrangement of parts thereof without departing from some of the essential features of the invention.

I claim as my invention:

1. A circuit breaker comprising stationary and movable contacts, a movable switch actuating member for actuating said movable contact, a link having one end pivotally mounted on a fixed pivot and the other end pivotally connected to one end of said switch actuating member to form a toggle, a trip member normally supporting said toggle in operative position, an operating handle movable to an open position and to a closed position, an overcenter spring operatively connected between said handle and said switch actuating

member, said overcenter spring being operable by said handle to cause opening and closing movement of said switch actuating member, a stored energy device releasable to actuate said trip member to a position to permit collapse of said toggle and automatic opening of said contacts, and a trip device operable to effect release of said stored energy device.

2. A circuit breaker comprising stationary and movable contacts, a movable actuating switch member for said movable contact, a link having an end pivotally mounted on a fixed pivot and the other end pivotally connected to one end of said switch actuating member to form a toggle, a rotatable trip member having a first position in which it cooperates with the knee of said toggle to normally restrain said toggle in an operative position, an operating handle movable to an open position and to a closed position, an overcenter spring having one end connected to said handle and the other end connected to said switch actuating member and movable overcenter by said handle to cause opening and closing movement of said switch actuating member, a spring operated member releasable to rotate said trip member to a second position in which said trip member permits collapse of said toggle to effect automatic opening movement of said switch actuating member, a trip device operable in response to overload currents to release said spring operated member, and a portion on said handle for engaging and rotating said trip member back to said first position.

3. A circuit breaker comprising stationary and movable contacts, a movable switch member mounting said movable contact at one end, a link having one end pivotally mounted on a fixed pivot and the other end pivotally connected to the other end of said switch member to form a toggle, a rotatable trip member having a first position in which it cooperates with the knee of said toggle to normally restrain said toggle in an operating position, an operating handle movable to an open position and to a closed position, an overcenter spring connected between said handle and said switch member and movable overcenter by said handle to cause opening and closing movement of said switch member, a spring operated member releasable to engage and rotate said trip member to a second position in which said trip member permits collapse of said toggle to effect automatic opening of said switch member, a trip device operable in response to overload currents to release said spring operated member, said handle when moved to said open position engaging and rotating said trip member back to said first position, and a projection on said trip member for engaging and resetting said spring operated member.

4. A circuit breaker comprising stationary and movable contacts, a movable switch member mounting said movable contact at one end thereof, a link having one end pivotally connected to the other end of said switch member to form a toggle therewith and having its other end pivotally mounted on a fixed pivot, a rotatable trip member having a first position in which it restrains said toggle in an underset position and rotatable to a second position to permit collapse of said toggle and automatic opening movement of said switch member, an operating handle movable to an open position and to a closed position to effect opening and closing movement of said switch member, an overcenter spring connected between said handle and said switch member, and operable to cause opening and closing movement

of said switch member, a biased releasable member operable when released to engage and rotate said trip member to said second position to permit collapse of said toggle and automatic opening movement of said switch member, a projection on said trip member for engaging said switch member and starting said switch member in opening direction, and a current responsive trip device operable in response to overload currents to release said biased member.

5. A circuit breaker comprising stationary and movable contacts, a movable switch member mounting said movable contact at one end thereof, a link having one end pivotally connected to the other end of said switch member to form a toggle therewith and having its other end pivotally mounted on a fixed pivot, a rotatable trip member having a first position in which it restrains said toggle in an underset position and rotatable to a second position to permit collapse of said toggle and automatic opening movement of said switch member, an operating handle movable to an open position and to a closed position to effect opening and closing movement of said switch member, an overcenter spring connected between said handle and said switch member, and operable to cause opening and closing movement of said switch member, a biased releasable member operable when released to engage and rotate said trip member to said second position to permit collapse of said toggle and automatic opening movement of said switch member, a projection on said trip member for engaging said switch member and starting said switch member in opening direction, a current responsive trip device operable in response to overload currents to release said biased member, and a projection on said handle for engaging and rotating said trip member back to said first position.

6. A circuit breaker comprising stationary and movable contacts, a movable switch member mounting said movable contact at one end thereof, a link having one end pivotally connected to the other end of said switch member to form a toggle therewith and having its other end pivotally mounted on a fixed pivot, a rotatable trip member having a first position in which it restrains said toggle in an underset position and rotatable to a second position to permit collapse of said toggle and automatic opening movement of said switch member, an operating handle movable to an open position and to a closed position to effect opening and closing movement of said switch member, an overcenter spring connected between said handle and said switch member and operable to cause opening and closing movement of said switch member, a biased releasable member operable when released to rotate said trip member to said second position to permit collapse of said toggle and automatic opening movement of said switch member, a projection on said trip member for engaging said switch member and starting said switch member in opening direction, a current responsive trip device operable in response to overload currents to release said biased member, a projection on said handle for engaging and rotating said trip member back to said first position, and a second projection on said trip member for engaging and resetting said biased member.

7. A circuit breaker comprising a switch member movable to open and close the circuit, a link having one end pivoted on a fixed pivot and the other end pivotally connected to one end of said switch member to form a toggle, a trip member

having a plurality of projections thereon and having a surface thereon normally engaging said toggle at a point adjacent the knee of said toggle to restrain the knee of said toggle in an operative position, said trip member having a recess therein movable to a position to permit collapse of said toggle, an operating handle movable to an open position and to a closed position to effect opening and closing movements of said switch member, an overcenter spring having one end connected to said handle and the other end connected to said switch member for operating said switch member, a releasable biased member operable when released to engage one of said projections and move said trip member to said position to permit collapse of said toggle and opening movement of said switch member, said biased member causing another of said projections to engage said switch member and start said switch member in opening direction, a trip device operable to release said biased member, said handle engaging a third projection on said trip member and resetting said trip member, said one projection during said resetting movement engaging and resetting said biased member, and said trip member during said resetting movement moving the knee of said toggle to said operative position.

8. A circuit breaker comprising relatively movable contacts, a switch actuating member movable to effect opening and closing of said contacts, a link having one end pivotally mounted on a fixed pivot and the other end connected to one end of said switch actuating member to form a toggle, a trip member cooperating with the knee of said toggle to normally restrain said toggle in an operative position, an operating handle movable to an open position and to a closed position to effect manual operation of said switch actuating member, an overcenter spring connected between said handle and said switch actuating member, said overcenter spring being movable overcenter by said handle to cause opening and closing movement of said switch actuating member about the knee of said toggle, said trip member maintaining the knee of said toggle stationary during said manual operation of said switch actuating member, a stored energy device releasable to engage and actuate said trip member to a position to permit movement of the knee of said toggle and collapse of said toggle to effect automatic opening movement of said switch actuating member and opening of said contacts, and a trip device operable to effect release of said stored energy device.

9. A circuit breaker comprising relatively movable contacts, a switch actuating member movable to effect opening and closing of said contacts, a link having one end pivotally supported on a fixed pivot and the other end pivotally connected to said switch actuating member to form a toggle, an operating handle movable to an open position and to a closed position to effect manual opening and closing of said contacts, an overcenter spring connected between said handle and said switch actuating member, said overcenter spring being movable overcenter across the knee of said toggle to cause opening and closing movement of said switch actuating member about the knee of said toggle, a trip member normally restraining said toggle in an operative position and holding the knee of said toggle sta-

tionary during the manual operation of said switch actuating member, a stored energy device releasable to actuate said trip member to a position to permit collapse of said toggle and automatic opening of said contacts, and a trip device operable to effect release of said stored energy device.

10. A circuit breaker comprising stationary and movable contacts, a switch actuating member movable to open and close said contacts, a link having one end pivotally mounted on a fixed pivot and the other end pivotally connected to said movable switch actuating member to form a toggle, an operating handle movable to an open position and to a closed position to manually open and close said contacts, an overcenter spring having one end connected to said handle and the other end connected to said switch actuating member operable by said handle to cause opening and closing movement of said switch actuating member, a rotatable trip member having a first position in which it cooperates with the knee of said toggle to normally restrain said toggle in an operative position, said trip member in said first position restraining the knee of said toggle stationary during manual operation of said switch actuating member, a spring operated member releasable to rotate said trip member to a second position in which said trip member permits collapse of said toggle to effect automatic opening movement of said switch actuating member, and a trip device operable in response to overload currents to release said spring operated member.

11. A circuit breaker comprising stationary and movable contacts, a switch actuating member movable to open and close said contacts, a link having one end pivotally mounted on a fixed pivot and the other end pivotally connected to said movable switch actuating member to form a toggle, an operating handle movable to an open position and to a closed position to manually open and close said contacts, an overcenter spring connected to said handle and to said switch actuating member operable by said handle to cause opening and closing movement of said switch actuating member, a rotatable trip member having a first position in which it cooperates with the knee of said toggle to normally restrain said toggle in an operative position, said trip member in said first position restraining the knee of said toggle stationary during manual operation of said switch actuating member, a spring operated member releasable to rotate said trip member to a second position in which said trip member permits collapse of said toggle to effect automatic opening movement of said switch actuating member free of said handle, and a trip device operable in response to overload currents to release said spring operated member, said handle when moved to said open position engaging and rotating said trip member back to said first position.
